UNITED STATES PATENT OFFICE

2,412,188

CLOTH DYEING MACHINE

Harry C. Wolfenden, Attleboro, Mass.

Application September 18, 1941, Serial No. 411,415

1 Claim. (Cl. 68—177)

1

My present invention is a novel and improved machine for dyeing cloth, yard or piece goods in various lengths or bolts.

In my development of improved dyeing apparatus, such for example as is illustrated in my prior and copending application Ser. No. 341,675, filed June 21, 1940, now Patent 2,292,811, Aug. 11, 1942, I have devised new and improved methods of dyeing and handling yarn and the like in a substantially closed receptacle, with a pump operating to produce a continuous circulation, and with means for effecting a constant agitation or bubbling thru the dyeing liquid, thus keeping the dyeing liquid uniformly mixed by reason of the turbulence caused by the bubbling action.

Furthermore, I utilize pre-heated vapors, gases, steam, and the like from the upper part of the closed receptacle, which are supplied to the lower part to effect the bubbling and agitation, thus preserving the temperature and saving greatly in the supply of heat or steam ordinarily required.

My present invention is directed particularly to handling various lengths of cloth or such textile material. Furthermore, I have devised novel and improved methods of adding fresh supplies of dyeing liquid from time to time by utilizing a portion of the dye already in the receptacle and during the continuous operation of the apparatus and while still operating as a closed receptacle.

This latter feature, viz., utilizing the liquid already in use for heating fresh supplies of dyes and chemicals is of particular importance, effecting a uniformity in the fresh dye supplied from time to time which, in my opinion, is a distinct advantage.

In carrying out my present invention, an apparatus of any suitable size or dimension to take a commercial length of yard- or piece-goods, or other textile material to be treated, is provided with means for automatically rotating the cloth within a closed receptacle, together with liquid-supplying devices, heating devices such as steam pipes or the like, and circulating means which will serve to withdraw the heated vapors and gases from the upper part of the receptacle and supply the same in the bottom portion under sufficient pressure to cause a bubbling agitation of the entire mass of liquid, all during the dyeing action and while the cloth is being continuously run therethru.

I also provide mechanism to readily feed in and feed out the cloth before and after being treated so as to handle the same with speed and facility.

2

I also provide novel means to enable a fresh supply of dyeing liquor to be added to the closed receptacle which is mixed in a chamber adjacent to the closed receptacle. In addition to this, I provide means for drawing some of the old liquor from the closed receptacle into the mixing chamber to be used with the new liquor which insures a more uniform admixture of the fresh supply when it is forced into the interior of the receptacle so that it will intermingle and mix more efficiently with the mass of liquid within the apparatus. Facilities are also arranged for pre-heating this new supply, if necessary, before pumping into the closed receptacle.

15 Referring to the drawings illustrating a preferred embodiment of the present invention:

Fig. 1 is a side elevational view of the apparatus viewing the same from the operator's left;

Fig. 2 is a side elevational view of the apparatus from the operator's right;

Fig. 3 is a vertical cross-sectional view on the line 3—3 of Fig. 1, and

Fig. 4 is a longitudinal cross-sectional view on the line 4—4 of Fig. 3.

25 As shown in the drawings, a receptacle of wood or other suitable material, comprising a bottom portion 1, sides 2—2, front 3, and back 4 is shown, the interior of the receptacle thus formed being provided with a metallic lining 5, as best shown in Figs. 3 and 4. This lining 5 is fitted closely adjacent the interior of the receptacle, except that it is in the form of a curved section between the rear part of the bottom 1 and back 4, as indicated at 6, to facilitate the feeding and sliding 30 of the material being treated during the dyeing operation, as will be further explained. The cover 10 is adapted to constitute a relatively tight top for the receptacle and for this purpose may be hinged as shown at 12—12 (Fig. 2) either back 35 or at one side, and a rubber gasket 14, or the like, is supplied on which the cover 10 rests.

40 A handle 15 will facilitate opening of the cover 10 and closing it, when desired. The metallic lining 5 may be of stainless steel and, preferably, is of a metal which will not be affected by the liquid contained within the apparatus. While any lining material may be sufficient, provided it does not discolor the dye or affect the dyeing operation, I find that stainless steel is best suited for this purpose.

45 Platforms 16 on the left and 17 on the right of the apparatus are provided for the convenience of the operator, as the height of the sides 2 is considerable and it is necessary to inspect and 50 clean the interior when the cover 10 is lifted, as

well as to prepare or thread in the articles to be treated.

In Fig. 4 I have illustrated a length of cloth 20 to be treated, which is led over the cross-rod 21 of a pair of rotatable barrel reels, which may have concave covering to help eliminate cloth-tangling, each comprising an axle 22 and a pair of discs 23, the rods 21 extending between said discs and the axles extending outside two bearings 30, as shown in Figs. 1 and 2. The cloth 20 is led in the direction of the arrow, Fig. 4, and accumulates in folds 25 along the inclined part 6 of the lining 5 and along the bottom part, and this cloth is kept in continuous movement by the rotation of the barrel reels, with concave covering, 15 22 and 23 and by joining the ends by lacings or other fastenings as indicated at 21. To rotate the reels 22 and 23, the axles extend thru the outside and beyond the bearings of the receptacle, see Fig. 2, and each is provided with a sprocket wheel 31 around which a sprocket chain 33 is led from a motor-driven wheel 34, whereby actuation by a motor 40 thru a reduction gear 35 acts to rotate the sprocket chain and, hence, the barrel reels operate in unison.

As illustrated in Fig. 2, the motor 40 is mounted on a bracket 39 on the right side of the apparatus from the position of the operator and the axle 36 to the reduction gear 35 is also mounted on said bracket and may be thrown into or out of operation, as desired, by the operator from a switch-board 41 at the front of the apparatus.

I divide the interior of the receptacle by a perforated metal screen 44, having a series of openings therethru as indicated at 46—46 extending throughout the entire width and substantially to the height of the interior of the receptacle at the front end, and with a curved top portion 48 to protect the cloth 20 from the heating, steam, supply and circulating pipes which are positioned between the screen 44 and the front of the apparatus, the curved part 48 also protecting the cloth 20 when it is fed into and out of the interior, as will be further explained.

Suitable dye is supplied within the receptacle 45 at approximately the level indicated at 50, although of course this level may be raised or lowered as desired.

An overflow pipe 51 is fitted at any convenient point, preferably at the front of the apparatus as shown, with its outlet slightly above the normal desired level 50, and a drain pipe (not shown) may be fitted at the bottom of the receptacle. At the front of the apparatus I fit a pair of brackets 55—55 spaced at each side of the width of the receptacle and extending outwardly to carry a rotatable takeaway roll, each comprising an axle 56 and guard 57, between which guards are rods 58.

This stick is rotated by a belt 60 from a pulley 59 on the outside of one end of the shaft, as shown in Fig. 2, the other end of the belt being fitted around a pulley 61 on the axle 22 of the forwardly positioned rotatable roll within the receptacle and thus securing its rotatable power from the motor 40.

Steam for heating is supplied from any suitable source of power thru a conduit 65 extending thru the side wall of the receptacle and downwardly, see Fig. 3, thru an internal pipe 66, which terminates in a cross-pipe 67 near the bottom of the receptacle and in the short space between the screen 44 and the adjacent front end, the cross-pipe 67 being perforated by a series of holes 68, as shown in Fig. 3. A valve 69 controls this sup-

ply of steam, as desired, and after the interior temperature of the receptacle and the liquid therein has been brought to the proper degree of heat, the steam may be shut off by operating the valve 69.

I may provide an automatic steam control and indicator to eliminate the use of the manual valve shutoff 69 by means of a branch or bypass 70 with an automatic governor designated generally at 10 71, having an indicator 72 and a handle 73 to adjust the same to the degree of temperature desired, which, when set will automatically control the inlet and shutoff of the steam supply, this being a well-known standard steam governor.

I also provide a branch 80 from the steam inlet conduit 65 controlled by a valve 81, which extends downwardly alongside the receptacle into a dye-mixing tank 82, so that when additional supplies of new dyeing liquid are to be supplied, the same may be mixed in a tank 82 heated by the steam supply thru manipulation of the valve 81, and then be pumped into the interior of the receptacle.

For this purpose an outlet from the tank 44 25 is fitted, as indicated at 85, which is preferably fitted underneath the tank 82, said tank being raised slightly by brackets 84—84 holding the tank on the platform 17, see Figs. 1 and 3. From the conduit 85, a branch pipe 86 leads to a pump 88, which in turn, by a pipe 89 thru a two-way valve 190 and a further pipe 91, extends into the interior of the receptacle and downwardly thru the conduit 92 to a crosshead 93 near the bottom of the tank between the screen 44 and the end, said crosshead being perforated at 95, Fig. 3.

The pump 88 is operated in either direction by a reversible motor 96, turning a pulley 97 and belt 98, which latter is led around a pulley 100

operating the pump 88. A two-way valve 101 is 40 fitted, as shown in Fig. 1, so that the operation of the pump 88 may be either to pump the contents of the tank 82 thru the pipes 85, 86, 89, 91, and 92 into the receptacle, or by reversing the motor to pump the contents of the receptacle thru the pipes 92, 91, 89, 86, and 85 into the tank 82, thus filling or partly filling the tank 82 and getting a heated mixture with the new supply for more uniform and continuous liquid dye after the general scheme of a regenerative process. A valve 190 is fitted in the conduit 89 with a short pipe 106 therefrom to discharge into the regenerative mixing tank 82, to divert a predetermined amount of the liquid dye during the liquid circulating operation, for testing or mixing, if desired.

Furthermore, I can utilize the pump 88 to effect a circulation directly within the receptacle itself. For this purpose, I provide a pipe 103 leading from the valve 101 into the interior of the receptacle thru an opening 105, which thus enables me to utilize the pump 88 to draw out liquid dye from the interior of the receptacle thru the openings in the crosshead 93 and thence thru the pipes 92, 81, 89, valve 101 and pipe 103 back into the receptacle thru the opening 105. I may also utilize this opening 105 as an additional outlet by providing an elbow and conduit above the level of the opening 105, as indicated at 106 and downwardly thru the discharge pipe 104. If this method of overflow is utilized, I would probably eliminate the overflow pipe 51 or would have to have this outlet at substantially the height of the pipe 106.

Thus it will be seen that I can utilize the pump 75 88 with an appropriate turning of the valves 190

5

and 101 and reversal of the pump to either pump the contents of the mixing and new supply tank 82 directly into the receptacle, or to effect a partial filling of the tank 82 by way of the pipe 106, or to pump the contents of the tank 82 into the receptacle or effect a circulation thru the receptacle of the liquid dye already therein.

Hot and cold water may be supplied, respectively, thru a pipe 140 for hot water, and 141 for cold, into a union 142 and thence into the inlet 143 in the rear wall of the receptacle, as shown in Figs. 1, 2, and 4.

Also, hot and cold water could be arranged to supply the same into the tank 82, conduits 145 and 146 being illustrated for this purpose from any suitable source of supply, with valves 147 and 148, respectively, as shown in Figs. 1 and 3. I may also desire to apply a clock 150 at the front of the machine, as shown in Fig. 1, for convenience of the operator in keeping track of the dyeing operations.

I prefer to utilize means which will automatically draw the vapors in the receptacle and above the level 50 of the dyeing liquid and supply the same under pressure to the bottom of the receptacle, thus producing a constant agitation, bubbling, or turbulence within the liquid to keep the same in proper admixture and condition, affording a more uniform dyeing action on the cloth.

For this purpose I arranged a perforated pipe 120 having a series of perforations 121 arranged therethru which is positioned substantially as shown in Fig. 3, and leads outside the receptacle thru a pipe 122, pump 123, and thence thru a return conduit 124 back into the receptacle and downwardly thru a pipe 125 to a pair of cross-heads 126 and 127 positioned at each side of the screen 44, as illustrated in Fig. 4, thus, simultaneously agitating the dyeing liquor at both sides of the partition, as well as shaking the cloth as it is raised out of the folds, and thus preventing creases or wrinkles, and insuring a more uniform dyeing action.

Each of these cross-heads is provided with a series of holes or openings 128. A motor 130 is arranged to operate the pump 123 thru a belt 131 or any other connection desired, so that vapors or steam from the upper part of the receptacle will be drawn thru the pipe 120 and forced by the pump 123 backwardly thru the pipe 125 and backwardly to the bottom of the receptacle, where the preheated vapors will thus be supplied at the bottom of the liquid dye thru the operation of the motor 130 or by any other suitable source of power.

Thus, the dye is kept in constant agitation by preheated means operating in a closed circuit, which thereby enables the steam to be shut off from the interior of the receptacle for relatively long lengths of time, while still maintaining the interior in proper heated condition and simultaneously supplying the bubbling or agitation desired.

When the cover 10 is opened, the cloth 20 can 65 be threaded into the receptacle over the rotatable

6

reels 23-23, with the ends joined together at 27; the cover then closed, and the mechanism started. Fresh dye can be supplied from time to time thru the mixing tank 82 and can be both 5 preheated and premixed by a supply or charge from liquid contained within the receptacle, as above explained.

After the proper length of time for the dyeing operation, the cover 10 is then lifted and the end of the cloth 27 located by continuing the rotation of the reels 23 until such end 27 is then reached; whereupon the lacing or other means uniting the two ends is severed and this end conducted up over the rounded corner 48 of the screen, and to the rotating roll on the axle 56 held by the brackets 55 along the dotted line 133, Fig. 4.

Thus, my improved apparatus is efficiently operated, conserving heat, saving time, penetrating the fabrics more thoroughly and uniformly, having the advantage of tending to create a partial vacuum, plus the fact that the machine is totally enclosed the greater part of the time, eliminating the steam getting into the building, 20 which is most detrimental to the construction of same, causing excessive rotting and deterioration which has always been a serious factor in dyehouse construction.

I claim:

30 Apparatus of the kind described for dyeing cloth and the like sheet articles, comprising a closed pressure-tight receptacle adapted to hold a mass of dyeing liquid therein, partially filling said receptacle, rotatable means within said receptacle adapted to carry and move articles to be treated in a predetermined direction therein, a curved support for said articles between the rotatable feeding means adapted to receive said articles on the upper part of the curved contour 40 of said support in the line of feed, said curved support being below the normal level of liquid within the receptacle, the progressive feeding action removing the articles from the lower portion of said curved support, heating means outside the receptacle extending into the inner portion adapted to supply heat to said dyeing liquid, a conduit leading within the receptacle from above the liquid level to below said liquid level, a pump operative to draw heated vapors thru said 45 conduit and supply same into the liquid under pressure from said pump, a vertically extending fixed screen adjacent one end of the receptacle 50 widthwise of the same protecting the articles being treated from contacting with said conduit and steam pipes, an auxiliary mixing tank outside of and adjacent said receptacle, and means to force liquid from the receptacle to the mixing tank and from said tank to the receptacle, while 55 maintaining said receptacle closed in pressure-tight condition and during the continuous movement of articles being treated within said receptacle, whereby a regenerative process of supply of fresh dyeing liquid is intermittently effected without interrupting the dyeing operations.

HARRY C. WOLFENDEN.
